UNITED STATES PATENT OFFICE.

JAMES A. PERRY, OF BIDWELL, IOWA.

TELEPHONE ATTACHMENT.

961,157.

Specification of Letters Patent. Patented June 14, 1910.

Application filed November 9, 1909. Serial No. 527,030

To all whom it may concern:

Be it known that I, JAMES A. PERRY, citizen of the United States, residing at Bidwell, in the county of Wapello and State of Iowa, have invented certain new and useful Improvements in Telephone Attachments, of which the following is a specification.

My invention relates to an attachment adapted to be applied to telephones whereby 10 a number of users may listen at the receiver of a telephone at one time.

The invention consists of a support for a telephone receiver upon which the receiver is adapted to be placed and used with the attachment, a sound chamber and a plurality of tubes extending from the sound chamber and preferably provided at their extremities with means whereby the ends of the tubes may be applied to the ears of the users.

20 My invention is shown in the accompanying drawings, wherein:

Figure 1 is a perspective view of my invention; Fig. 2 is a fragmentary section thereof; and Fig. 3 is a perspective view of a 25 modification.

Corresponding and like parts are referred to in the following description and indicated in all the views of the drawings by the same reference characters.

30 Referring to the figures, 2 designates a base plate having thereon a casing 3, said casing formed in its interior with a sound chamber 4 of any desired character, which is closed at its lower end, preferably by a plate

35 5 provided with a plurality of openings in which are inserted the inner extremities of a plurality of sound conducting tubes 6, these tubes preferably being of rubber. The end of each tube 6 is provided with a cup 7

40 through which the tube projects, the cup being designed to be applied to the ear of the user and the projecting tube entering the opening of the ear so that the sound is carried more directly to the auditory nerve.

45 Preferably, the casing 3 is supported upon the legs 8, though this is not necessary, as the attachment might be applied to a wall or other convenient support by means of the base plate 2. I have shown the casing 3 as

50 formed of a block of any suitable material, having the chamber 4 formed therein, this chamber being preferably tapered toward its outlet end. The upper face of the casing 3 is formed so as to contact with the rim of a telephone receiver when the receiver is supported upon the casing 3 so that the vibra-

tions of the diaphragm in the receiver will be communicated to the air inclosed within the chamber 4 and to the air in the tubes 6.

In order to provide means for the support 60 of a telephone receiver, I provide a base plate 2 with the receiver holder or clamp 10. This is preferably formed of opposed resilient wires inserted at their inner ends in the base plate 2, then crossing each other and 65 then outwardly extended to form opposed clamping members, the wire or rod forming the clamping members being bent so as to inclose the barrel of the telephone receiver, the outer ends of the wire being outwardly bent 70 so as to permit the easy insertion of the receiver. The upper face of the casing 3 is preferably provided with a ring 11 of rubber, felt or other suitable material which fits the rim of the receiver so that the receiver 75 will have a good air tight connection with the upper face of the box 3 so that no sound may be lost.

The operation of my invention will be obvious. When it is desired that a number 80 of people shall hear the message which is coming over the telephone wire, it is only necessary to remove the receiver from its hook and place it within the holder with the rim of the receiver resting upon the felt ring 11. 85 Those who are desirous of listening to the message can each take one of the rubber tubes 6 and placing the ear piece thereon to the ear listen to the conversation.

90 My invention is simple, can be easily applied, does not require any change in the telephone now in use, permits the telephone to be used as ordinarily and yet permits on an occasion a number of listeners to hear what is said on the phone.

95 It will be obvious that the tubes or pipes 6 may be of any desire length and might extend to a number of different places in a building so that persons in different parts of the same building could hear whatever 100 was being telephoned to the central office, and this without any change in the usual telephone connections.

While I have shown what I believe to be the preferable form of my invention, I do 105 not wish to be limited thereto as it is obvious that many changes might be made therein without departing from the spirit of the invention.

Having thus described the invention, what 110 is claimed as new is:

1. An attachment for telephones, com-

2
prising a support, a chamber mounted on the support, one end of said chamber being open, a plurality of tubes extending from the other end of the chamber, a ring of yielding material mounted upon the open end of the chamber and adapted to engage with the rim of a telephone receiver, and a receiver holder mounted adjacent to the open end of the chamber and adapted to hold a telephone receiver with its rim in engagement therewith.

2. An attachment for telephones, comprising a base plate, a casing mounted on the base plate and projecting therefrom; said casing having therein a chamber, one end of the chamber being open, a plurality of conducting tubes extending from the other end of the chamber, a ring of yielding material mounted on the open end of the chamber and adapted to engage with the rim of a telephone receiver, and a clamp

mounted on the base plate and adapted to engage the barrel of the telephone receiver and hold the receiver with its rim in engagement with said ring. 25

3. An attachment for telephones, comprising a base plate, a casing mounted on the base plate, said casing being hollow to form a sound chamber open at one end, a plurality of tubes extending from the other end of the sound chamber, a clamp mounted adjacent to the open end of the chamber and adapted to support a telephone receiver with its rim in contact with the open end of said casing, and legs for supporting said 30 casing and base.

In testimony whereof I affix my signature in presence of two witnesses.

JAMES A. PERRY. [L.S.]
